Fixture Holder for Roll Roofing

Fred J. Stephens, Park Ridge, Ill., and Wesley T. Tillotson, Huntington Park, Calif., assignors to United States Gypsum Company, Chicago, Ill., a corporation of Illinois

Application May 9, 1942, Serial No. 442,301

6 Claims. (Cl. 206—47)

This invention relates to fixture holders or cartons for use with roll roofing and the like, whereby a can of cement and a bag of nails may be supported as a unit within the hollow interior of a roll of roofing paper where they will be readily available for use when needed.

In the shipment and storage of roll roofing, it is the practice to place a container of cement and a bag of nails or other fixtures used in applying said roofing, in the amounts needed, within the usual hollow interior of a roll of roofing paper. Each end of the roll is thereafter covered with a cap of fabric or paper. This cap is usually extended down along the sides of the roll adjacent each end to give added strength and so that it may be firmly secured in place.

It will be apparent that with fixtures loosely placed in the hollow interior of such a roll or contained in a holder which is loosely free to shift in this hollow interior, the cap or covering at each end of the roll will be subjected to strains and penetrating impacts which, unless such covers are very strong and substantial and correspondingly expensive, will soon cause them to be punctured and the fixtures possibly lost.

Heretofore various methods of supporting fixtures in the hollow interior of a roll of sheet material to prevent shifting therein have been proposed. However, such methods ordinarily require the use of resilient metal strips or wires in order to function. There are a number of objections to the use of metal for this purpose, as it is heavy, expensive and currently unavailable.

The fixture holder or carton of the present invention may readily be made from sheets of fibrous material, such as cardboard or corrugated board and, because the blanks required are simply rectangular strips and are of uniform dimension and simple design, no complicated machines or manufacturing operations are necessary in their manufacture. It is, therefore, an important feature of the present invention that the blanks may be made by a simple cutting knife and without the use of special cutting dies. This also eliminates any loss due to excess or waste material.

If desired the holder may be formed from scrap or waste pieces of roofing material and, when such material is used for this purpose, it should be disposed with the rough or pebbled side out. This increases the degree of frictional engagement against the inside walls of the roll of roofing material by which the holder is retained in place.

It is an object of the present invention to provide a fixture holder which will retain the fixtures in place in a roll of roofing material and will prevent the possibility of puncturing the end caps placed over the ends of rolls of roofing material, thus permitting the use of lighter and less expensive caps.

It is a further object of the present invention to provide a fixture holder which is cheap and simple to manufacture, which is light in weight and is sufficiently strong and durable to protect its contents.

Another important advantage of the present invention is the fact that it may be collapsed when not in use whereby the holder may be folded flat for shipment or storage, so as to occupy a minimum of space.

Other objects and advantages will appear from a consideration of the following detailed specification. For a more complete understanding of this invention reference may now be had to the accompanying drawing in which:

Figure 1 is a perspective view of one embodiment of the present invention.

Fig. 2 is a sectional view partially in elevation of an embodiment similar to that shown in Fig. 1, but wherein there is employed a slightly different method of retaining the bag of nails in place, and wherein the holder is formed of granule-surfaced, flexible roofing material.

Fig. 3 is a longitudinal sectional view partly in elevation through one end of a roll of roofing paper showing the fixture holder in place.

Fig. 4 is a transverse sectional view taken along line 4—4 of Fig. 3.

Fig. 5 is a perspective view partially in section of a fixture holder folded for shipment or storage.

Fig. 6 is a fragmentary plan view of a portion of a carton blank wherein a projecting tab forms an integral part thereof.

Fig. 7 is a detailed sectional view partially in elevation taken on line 7—7 of Fig. 3.

Referring to the drawing in detail, the embodiment illustrated comprises an elongated strip of material 1 which is provided with a number of transversely extending scored lines, along which the strip may be folded as shown, to provide a carton having a hollow interior for the accommodation of fixtures.

When the strip 1 is so folded, there is provided an open-sided carton having a bottom 2, opposed upwardly extending sides 3 and 4, and inwardly directed sloping top members 5 and 6 which terminate in an upstanding handle 7.

formed by the terminal portions 8 and 9 of the strip. These portions 8 and 9 may be secured together by any suitable means, such as glue, or may be stapled together as by the staple 10 shown.

Into the carton formed by folding strip 1 as above indicated, may be inserted a base strip 11 comprising a short strip of the same sheet material from which the carton is formed. The width of this base strip is preferably equal to the distance between the scored lines on the base portion 2, and the length of this base strip is preferably somewhat longer than the width of the strip 1 whereby its ends 12 and 13 protrude from opposite sides of the carton. The base strip 11 may also be creased transversely along lines 14 and 15 if desired and may be retained in place by the contents of the carton or may be stapled or glued in place. Instead of the separate base strip 11 the strip 1 may be provided with oppositely disposed laterally extending protruding tabs 11a which may be formed as integral extensions from the bottom 2 of the carton.

The fittings to be contained within the carton ordinarily comprise a can of cement 16 and a bag of nails or other fasteners 17 which may be placed therein as shown. The width of the bottom member 2 and of the strip 11 is preferably such that the circumferential beads 18 and 19 at each end of the can 16 press into the material of the walls 3 and 4 and the can is thereby more firmly held in place.

With the can of cement and bag of nails in place, the carton may be picked up by the handle and forcefully inserted into the hollow longitudinal opening in a roll of roofing paper. During this operation, the projecting ends 12 and 13 of the strip 11 will engage the inner wall of the roll and will be bent upwardly so as to be inclined as shown in Fig. 3. These ends are thereby snugly urged into engagement with the inside walls of the roll of roofing paper and strongly resist any tendency of the fixture holder and its contents to be jarred or displaced during shipment of the roll of paper.

It will be noticed that with the above arrangement, in order to remove the fixture holder and its contents from the roll of roofing paper, it is only necessary to reach into the end of the roll, grasp the handle 7 and bodily withdraw the holder and contents from the roll. This operation requires only sufficient force to overcome the aforesaid resistance due to the engagement of the holder with the inside walls of the roll.

Though the above description refers particularly to the frictional engagement afforded by the upturned ends 12 and 13 of strip 11, yet it will be apparent that, when proportioned as shown, the vertical corners 20 of the side walls 3 and 4 may be also compressed and displaced by the operation of inserting the holder into the roll of roofing whereby a frictional resistance to displacing movement due to shocks or jars is provided.

The open end 11a of the bag 17 may be folded over, as shown in Fig. 1, and retained in place by its fit within the carton. However, if desired this bag end may be secured in place, as shown in Fig. 2, where it is shown brought upwardly between the terminal portions 8 and 9 of the strip 1 and secured in place by the staple 10 or other fastening means employed. With the latter arrangement the bag is securely fastened against accidental displacement or loss and the contents are kept intact.

After the holder has been extracted and the fixtures employed in applying the roll of roofing, the fixture holder, being of extremely cheap construction, may ordinarily be discarded; however, if desired the fixture holder may be folded to a flat package of minimum size as shown in Fig. 5 to be stored or returned to the factory for re-use.

Because of the manner in which the fixtures are kept from shifting and puncturing through the usual cover at the end of the roll, a much thinner and consequently less expensive cover 21 may be employed.

As previously stated, the holder may be formed from any suitable strip material, and there is thus illustrated in Fig. 2 an embodiment wherein strips of the usual granule-surfaced, flexible, felt roofing material are employed. One side of this material is roughened by the granules 22, and these granules serve to increase the degree of frictional contact of the holder with the inner surface of the roll.

It is intended, of course, that the invention should not be limited to the specific embodiment or embodiments disclosed herein, since modifications may be made, and it is contemplated, therefore, by the appended claims to cover any such modifications as fall within the true spirit and scope of this invention.

Having thus described this invention, what is claimed and desired to be secured by Letters Patent is:

1. A two-piece collapsible holder for roll roofing fixtures, said holder comprising a strip of formable material, the ends of said strip being joined together to provide a carton open on two sides, and a strip of material transversely positioned within said carton so that its ends project therefrom.

2. A carton for the support in the hollow interior of a roll of roofing material of cement, nails and similar roll roofing fixtures comprising an elongated rectangular strip of deformable material folded along transverse lines to form a carton open on opposed sides, a second strip of similar material disposed transversely of said first strip and having its ends protruding from the open sides of said carton, said protruding end portions serving to frictionally engage the inner walls of a roll of roofing and retain said carton in place.

3. A carton for the support in the hollow interior of a roll of roofing material of a can of cement and a bag of nails or like roll roofing fixtures, said carton comprising an elongated rectangular strip of deformable sheet material folded along transverse lines to form a carton having a bottom, two side walls and a top, and a second strip of similar material disposed transversely of said first strip and having its ends protruding from the carton.

4. A collapsible fixture-enclosing carton for the support in the hollow interior of a roll of roofing material, of cement, nails and other sheet material applying fixtures, said carton comprising an elongated substantially rectangular strip of granule-surfaced roofing material, said strip being folded along transverse lines to form a carton having a bottom wall, vertically disposed side walls and a top wall, and protruding portions extending from said bottom wall of said carton to be deformed upon insertion of said carton into the hollow central opening in a roll of roofing material so that it will be frictionally retained therein, said carton being formed with the gran-

ule surface disposed outwardly to increase the degree of frictional engagement with said roll.

5. A fixture assembly and carton for unitary insertion in the hollow interior of the usual roll of roofing material comprising a strip of formable material reversely formed and enclosing a container of cement and a bag of nails, said strip forming side walls along said fixtures and the terminal ends of said strip being secured together to form a handle, the usual open end of said bag of nails being inserted between the ends of said strip and fastened thereby.

6. A fixture-enclosing carton to support fixtures within the hollow interior of a roll of sheet material, said carton being formed from a strip of sheet material and comprising a bottom wall, side walls and a top wall, said bottom wall having a strip of deformable sheet material disposed transversely thereacross, an end of said transversely disposed strip projecting from said carton to frictionally engage the inner surface of said roll of material and retain said carton in place.
